(57) **CLAIM**

I claim the ornamental design for a paddle, as shown and described.

DESCRIPTION

FIG. 1 is a top, perspective view of the a paddle; the view showing my new design;

FIG. 2 is a front elevation view thereof;

FIG. 3 is a rear elevation view thereof;

FIG. 4 is a side view thereof;

FIG. 5 is a side view thereof;

FIG. 6 is a top view thereof;

FIG. 7 is a bottom view thereof; and,

FIG. 8 is a bottom, perspective thereof.

The broken lines in the drawings depict portions of the paddle that form no part of the claimed design.
